MOLD FOR TYPE CASTING MACHINES

John Joseph Christman, Trenton, and Frederick David Klapproth, Pennsaltiken, N. J., assignors to Pennland Printing Company, Philadelphia, Pa., a corporation of Pennsylvania

Application December 2, 1948, Serial No. 63,002

3 Claims. (Cl. 199—55)

1

This invention relates to improvements in type casting machines and relates more particularly to an improvement in the mouthpiece assembly.

An important object of the present invention is to form the back of the type mold in such a fashion as to cause all excess metal which is cast in the mouthpiece openings, including the vents, to adhere to the mold, thus leaving no deposit adhering to any part of the mouthpiece.

Another important object of the invention is to provide an improved mold which permits the use of relatively harder alloys for the type and to run this metal at a lower temperature than has heretofore been considered feasible.

In each cycle of operation in a type casting machine, the back of the type mold becomes locked against the mouthpiece to allow for feeding the molten metal through the openings in the mouthpiece and into the cavity in the mold. The mold has on its front face a composed line of matrices to produce a type bar or slug bearing the letters corresponding to the intaglio letters of the matrices.

The flat, meeting faces of the mouthpiece and the mold, and the walls of the cavity and the matrices at the front end thereof, form a substantially air-tight chamber and the effective venting of air from this chamber as the metal flows into it has always been a problem. Transverse vents are provided on the face of the mouthpiece between the openings through which the molten metal passes. These vents are smaller at their ends than at their centers in order to allow some of the metal, which must inevitably flow out through these ends, to "freeze" upon contact with the relatively colder mold and with the air just outside the vents rather than to continue to run as would be the case if the vent terminals were relatively large.

The use of harder type metals, i. e., those containing a relatively higher concentration of antimony and tin has long been the aim in type composition. In addition to increasing the hardness of finished slugs, a higher proportion of antimony also tends to cause the lead to set or solidify more quickly. Also the presence of a higher concentration of tin imparts added toughness to the slug. The harder the slug, the sharper the print and the longer the effective life of the type. These alloys, however, have a greater tendency to adhere to the mouthpiece and particles frequently remain in the vents to cause trouble. The tendency to so adhere is not even absent in ordinary type metal. It is for this reason that elaborate devices have been developed

2

for cleaning the mouthpiece although these devices have not proven too satisfactory with either the conventional or with the harder alloys. Various other expedients have been tried including greater pressure on the springs which operate the pump but the results are largely the same and after periods of successful operation bad results will unexpectedly start with no apparent reason. The most serious of these difficulties is the production of slugs having fatal air holes.

The presence of these air holes renders the slugs largely useless or at least usable for only a short period of time. One of the problems, then, is to effectively vent the air without letting any appreciable quantity of metal to escape through the small bleed slots at the bottom of the vents. If particles of the metal remain in the vents when the mold departs from the mouthpiece these particles move downwardly before the start of the next cycle of operation, due to the heat recovery of the mouthpiece and stay in the vent bleed slots. On the next cycle the cold mold coming in contact with the mouthpiece solidifies this metal and closes the vent bleed, thus preventing the air from escaping which causes air holes in the slug. When the softer metals are used the portions of the cast entering the vents generally break away clean and remain integral with the slug. When the harder metals are used, however, there is a greater tendency for particles originally forming part of the vent cast to break away from the slug and remain in the vents.

Heretofore it has always been considered imperative to form the back face of the mold which is engaged by the mouthpiece, perfectly flat and mirror smooth. After each casting operation the excess metal is trimmed from the back of the mold and the back face is again smooth for the next cast.

In accordance with the present invention the back face of the mold is formed with plural recesses which are generally aligned with the vents in the mouthpiece. The molten metal enters these recesses and stays there although if it pulls out in one casting operation it is filled on the next. Thus, all the metal cast in the vents adheres to the metal in the back-face recesses and the face of the mouthpiece is always clear and free from metal particles. The reason why all of the metal leaves the vents is because it has a greater adhesion for the metal in the mold recesses than for the walls of the vents.

When the mold leaves the casting station the excess metal on the back face is sheared off in

the usual fashion and some of the metal always remains in the recesses for the next operation.

A further object of the invention is the provision of novel means whereby the terminals of the vents may be made larger than has heretofore proven satisfactory, thus venting the air more satisfactorily and quickly. This desired result is achieved by virtue of the fact that a perfectly clean mouthpiece after each casting cycle enables the molten metal to be maintained at a lower temperature. The metal being thus cast at a lower temperature is less fluid and the bleed vents can be larger while having a smaller amount of metal passing therethrough. This result is obtained with the harder alloys in a high degree and to only a slightly lesser degree with ordinary alloys. The slugs in all instances have a finer grain, a better and sharper face and porosity is a rarity.

In the drawing:

Fig. 1 is a transverse section taken through a metal pot, attached mouthpiece, and slug casting mold and illustrating the present invention.

Fig. 2 is a broken section taken through the mouthpiece and mold of the present invention.

Fig. 3 is a broken plan view of the face of the mouthpiece.

Fig. 4 is a broken plan view of a slug casting mold embodying the present invention.

Fig. 5 is a broken section taken through the mouthpiece and mold of the present invention showing one type of recess in the mold.

Fig. 6 is a similar section showing another type of recess in the mold.

Fig. 7 is a broken plan view of another type of recesses in the mold.

Referring now more particularly to the drawing, there is shown in Fig. 1 the usual metal pot 10 generally used in commercial type casting machines, the molten metal 11 contained therein being forced under pressure by means of a piston 12 through a delivery passage 13 in the throat section 14. This throat section is fitted with the usual mouthpiece 15 having a slightly raised face 16.

The mouthpiece is further provided with feed holes 20 communicating with the delivery passage 13. These holes are arranged in spaced relation and between the holes are the transverse vents 21. The vents are generally triangular in transverse section and taper inwardly at their opposed terminals. The upper ends of the vents, when viewed as in Fig. 3, terminate short of the upper edge 22 of the raised face 16 and their lower terminals 23 terminate at the lower edge 24 of the raised face and, though narrow, they are sufficiently wide at such lower terminals to give approved air venting action.

A slug casting mold 25 is formed with a longitudinal cavity 27 defined by walls 26 between which the slug is cast. It is further provided with suitable openings 30 for attachment to a rotatable disc (not shown). Suitable means (not shown) are provided for supporting a composed line of matrices 31 while the back face 32 of the mold is locked in sealed, face-to-face engagement with face 16 of the mouthpiece. The raised face 16 of the mouthpiece, except for the holes 20 and vents 21 is a perfectly smooth, plane surface. All the foregoing is conventional.

The two portions 32 and 33 constituting the back face of the mold 25 are slightly raised above surfaces 34 and 35. These surfaces 32 and 33 have heretofore been perfectly smooth, plane surfaces. In accordance with the present invention,

however, they are provided with recesses 36 which are aligned with the vents 21 when the two members are in the face-to-face engagement of Fig. 1.

In Fig. 5 the recesses are shown as milled slots which are generally triangular in transverse section whereas in Fig. 6 the recesses 40 are slightly undercut and are of a dovetail contour. Also in Fig. 7 small holes 41 are provided instead of the transverse slots.

In the event that the triangular milled slots 36 of Figs. 4 and 5 are employed the upper terminals of the slots may be disposed at or near the upper ends of the vents 21 and in any event they should not extend as high as the upper edge 22 of raised face 16 of the mouthpiece when the members are in the position of Fig. 1. Similarly, the lower ends of the recesses should not extend down as far as the lower edge 24 of such raised face since this would give supplemental venting action and vents 21 adequately take care of this venting action.

The same limitation with regard to length should be embodied in the dove-tail arrangement of Fig. 6. The width of the mold slots on the back face of the mold may vary from a width substantially the same as the width of the vents as shown in Fig. 5 to a somewhat lesser width as shown in Fig. 6 or to a still narrower width as shown in Fig. 4 compared to the vent widths shown in Fig. 3. In the event that the holes 41 of Fig. 7 are employed the holes should be wholly confined in the areas defined by the several vents.

The operation of the type casting machine is carried out in the same fashion as heretofore. When the slug is cast the mold is locked against the mouthpiece and the molten metal flows through the feed holes 20 in the mouthpiece and into cavity 21. As the cavity fills, the air bleeds through the lower ends of the vents. The metal also fills the vents in the mouthpiece as well as the recesses in the back face of the mold. A small quantity of the metal also passes through the lower ends 23 of the vents as the cavity becomes filled.

After the metal has solidified the mold leaves the mouthpiece and every vent cast firmly adheres to the metal which is cast in the companion recess in the mold. Since no metallic particles remain in the vent openings the face of the mouthpiece is perfectly clean for the next operation.

The excess metal is trimmed from the back of the mold in the usual fashion, which operation, however, does not generally remove all the metal from the recesses. Even if such metal is removed during the trimming operation it is of no consequence since on the next cast the metal again enters the recesses and functions in the manner just described.

While three forms or embodiments of the invention have been shown and described herein for illustrative purposes, and the construction and arrangement incidental to specific applications thereof have been disclosed and discussed in detail, it is to be understood that the invention is limited neither to the mere details or relative arrangement of parts, nor to its specific embodiments shown herein, but that extensive deviations from the illustrated forms or embodiments of the invention may be made without departing from the principles thereof.

What we claim is:

1. In a mold for a type casting machine having a type cavity and wherein the back face of the

mold is arranged to be locked to a mouthpiece associated with a metal pot and having openings for delivery of the metal to the cavity, and air vents disposed between such openings, such back face having undercut recesses therein which are aligned generally with the air vents and which communicate with the mold cavity, the type metal being adapted to flow into and remain in such recesses and form a bond with metal cast in the vents to withdraw such cast metal upon 10 departure of the mold from the mouthpiece.

2. In a mold for a type casting machine having a type cavity and wherein the back face of the mold is arranged to be locked to a mouthpiece associated with a metal pot and having openings for delivery of the metal to the cavity, and air vents disposed between such openings, such back face of the mold having spaced recesses therein which extend generally transversely from the mold cavity on each side thereof and which communicate with such mold cavity at their inner terminals, such recesses being generally aligned with the air vents, the type metal being adapted to flow into and remain in such recesses and form a bond with metal cast in the mold cavity and in the vents and to withdraw such metal cast in the vents upon departure of the mold from the mouthpiece.

3. A self-cleaning mouthpiece-mold assembly for type casting machines wherein the mold has a type cavity and the mouthpiece has openings

for delivery of the metal to such cavity and air vents between the holes to release air from the cavity, the back face of such mold having undercut recesses therein which extend transversely from the mold cavity and which communicate with the air vents and which receive metal therein, said recesses being generally aligned with the air vents and being open to the mold cavity, such metal forming a bond with the metal cast in the vents to remove such metal from the vents upon departure of the mold from the mouthpiece.
